UNITED STATES PATENT OFFICE

HENRY CONRAD HEBIG, OF ROSELLE PARK, NEW JERSEY, ASSIGNOR OF FIFTY-FIVE PER CENT TO NELSON LITTELL, OF NEW CANAAN, CONNECTICUT

FOOTWEAR

Application filed August 30, 1929. Serial No. 389,341.

This invention relates to new and useful improvements in footwear, particularly bathing shoes, bedroom slippers or sandals made substantially of sponge rubber.

5 It is a principal object of this invention to construct a pair of bathing sandals, bedroom shoes or slippers substantially entirely out of sponge rubber for use in bathing to prevent slipping on smooth surfaces and to provide 10 comfortable lounging slippers.

It is another object of my invention to provide a bathing sandal or shoe having a sole of porous sponge rubber which does not slip on smooth surfaces.

15 Another object of this invention is to provide an economical method whereby a shoe or slipper may be formed from sponge rubber.

Another object of my invention is to provide a rubber sponge slipper, or a slipper with 20 a rubber sponge sole, which may be used either at the beach as a bathing slipper or in the home as a lounging slipper or both.

Other objects of my invention will appear from the following description thereof taken 25 in connection with the attached drawings illustrating preferred forms of embodiment thereof and in which—

Figure 1 is a perspective view of an all-sponge rubber shoe preferably formed of one 30 piece of sponge rubber.

Figure 2 is a central section thru the shoe shown in Fig. 1, shown in use.

Figure 3 is a perspective view of a modified form of all-rubber sponge shoe.

35 Figure 4 is a section of the portion of the shoe shown in Fig. 3 taken substantially on the line 4—4 thereof.

Figure 5 is a still further modified form of shoe; and

40 Figure 6 is a section thru the toe portion taken substantially on the line 6—6 of Figure 5.

I have found that commercial rubber sponge can be formed into bathing and lounging slippers which are more comfortable to wear than the ordinary bedroom slipper and which when used for bathing do not cause undue perspiration of the feet and effectively prevent slipping on the bathroom floor or 50 in the bath tub or at the beach.

I have therefore constructed a shoe or slipper 10 as shown in Fig. 1 which may be made out of porous sponge rubber. It particularly comprises the upper portion 10^a and the lower portion 10^b preferably formed from 55 a single block of rubber sponge although it may be formed in separate parts glued together. The opening 12 is adapted to receive a foot of the wearer and the resilience of the rubber is sufficient to cause it to cling to the 60 foot 14 as shown in Fig. 2. This rubber shoe may be formed by molding or by cutting a sufficiently large block of sponge rubber with a knife to form the outer side walls and sole and then by forcing the inner portion, to be 65 removed, out and above the wall portion which is to remain, the portion to be removed can be severed with a sharp knife and as the rubber regains its natural position, the suitable depression for receiving the foot will 70 remain.

When placing the shoe on the foot, particularly for bathing, it will be found that the rubber has a high coefficient of friction on the surface with which it may contact and does 75 not easily slide. Being porous, however, it does not stick to the surface and can be raised and moved with facility and also absorbs any moisture due to perspiration of the foot.

This shoe has an added feature that when 80 the bather's foot is raised and lowered in the water 16, diagrammatically shown in Fig. 2, the water will pass thru the porous shoe and pass between the toes to produce an added cleansing effect or when worn in the home 85 the porous rubber will permit passage of air through the walls thereof in walking to permit ventilation. The water will also pass up the sides of the foot and after stepping up and down several times, particularly in 90 soapy water, it will be found that the foot cleans itself.

The shoe may be made in one single piece of rubber, as shown in Figures 1 and 2 or it may be made from several pieces as shown in 95 Fig. 3. These pieces comprise the toe portion 20, the heel or ankle portion 22 and the sole or bottom portion 24. The toe and the ankle portion may be suitably formed and joined along the line 26 by any preferred form of 100

cement or by sewing, vulcanizing or the like and the combined top portions 20 and 22 may be secured to the sole 24 by cement or sewing or other means along the line 28. Under such construction, the shoe may take various shapes and may be made out of convenient narrow material and in properly varying sizes by properly cutting suitable patterns. This shoe will have the same general qualities as the preceding form but is easier to manufacture, as such bulk quantities of rubber are not required. It is also possible to use different materials for the upper and sole portions of the shoe. Porous sponge rubber will be used on the sole.

If a canvas top is desired, this may be formed as shown in Fig. 5, which similarly comprises a toe portion 30, heel or ankle portion 32 and sole portion 34. If a canvas shoe is used the toe and ankle portions 30 and 32 respectively, will be the only portions made of the canvas, the bottom portion 34 being of the heretofore mentioned sponge rubber. It is necessary that the bottom be of very porous sponge rubber in order that it will not slip on smooth surfaces and will permit the water to pass over the wearer's foot. The canvas top portion of the shoe shown in Fig. 5, can preferably be sewed, as shown at 36 in Fig. 6 to the bottom portion and eyelets for laces may be provided so that the shoe can be secured to the wearer's foot.

It will be found that a shoe such as this is particularly desirable for use in shower baths and for children standing in bath tubs and for many other places where large quantities of soapy water or extremely smooth surfaces, such as porcelain or enamel surfaces require a shoe on the wearer's foot to prevent slipping. It is also particularly desirable when taking shower baths as the limited walking of the bather, will not only repeatedly cause the water to pass thru the shoe to wash the bather's foot, but accidental stepping on the soap cake, inadvertently dropped on the floor, will not cause a serious fall.

When used as an ordinary bedroom slipper the rubber sponge will be found to be light, comfortable and durable, providing a warm ventilated enclosure for the foot which is noiseless for walking absorbs any perspiration of the foot and is soft to the touch.

It will be understood that the article described may be made up in many various ways as a shoe, slipper, mule or scuff or booties and may have all or only a portion thereof made of sponge rubber and that other modifications may be made. It is my intention to consider within the scope of this invention, similar rubber sponge devices adapted for the similar purposes hereinbefore mentioned unless otherwise excluded by the following appended claims.

I claim:

1. A shoe having a sole formed of sponge

rubber which is of substantially uniform porosity and is provided with intercommunicating openings extending from the interior to the exterior whereby air and water may freely pass therethrough in both directions.

2. A shoe having an upper and a sole formed of sponge rubber which is of substantially uniform porosity and is provided with intercommunicating openings extending from the interior to the exterior whereby air and water may freely pass therethrough in both directions.

3. A shoe having a sponge rubber upper of substantially uniform porosity with relatively small intercommunicating pores which render the rubber porous and absorptive throughout, the pores opening on the inner-surface being adapted to contact directly with the foot and those on the exterior being exposed to the atmosphere whereby air may pass through the pores into the shoe to ventilate the foot and perspiration of the foot will be absorbed.

In testimony whereof I have affixed my signature to this specification.

HENRY CONRAD HEBIG.
